CALCULATING MACHINE CASING

Richard W. Pitman, Laverock-Hillcrest, Pa., and Lurelle V. A. Guild, New York, N.Y., assignors to Underwood Corporation, New York, N.Y., a corporation of Delaware

Application April 2, 1958, Serial No. 50,308

Term of patent 14 years

(Cl. D64—11)

FIG. 1

FIG. 2

FIG. 3

FIG. 4

Figure 1 is a front perspective view of a calculating machine casing showing our new design;

Figure 2 is a rear perspective view thereof;

Figure 3 is a side elevational view of the casing shown in Figure 2; and

Figure 4 is a front elevational view thereof.

The essential features of our design reside in the portions shown in solid lines on the drawing.

We claim:

The ornamental design for a calculating machine casing, as shown and described.
